JOSEPH F. LAMB, OF NEW BRITAIN, CONNECTICUT, ASSIGNOR TO LANDERS, FRARY & CLARK, OF NEW BRITAIN, CONNECTICUT, A CORPORATION OF CONNECTICUT.

ELECTRIC RADIATOR.

Application filed June 6, 1919. Serial No. 302,177.

The present invention relates to a heater for warming air and the invention has as its object to produce a device of the character described having features of novelty and advantage.

In the drawings:—

Fig. 1 is a front view of the complete heater.

Fig. 2 is a side view in central vertical section.

Fig. 3 is an enlarged sectional view taken longitudinally through the heating unit.

Fig. 4 is a sectional view of the heating unit taken on a plane at right angles to the plane of Fig. 3.

Fig. 5 shows enlarged detail views, partly in section, of portions of the guard.

Fig. 6 is an enlarged view showing the means for attaching the guard to the reflector, and

Fig. 7 is a top plan view of two complete devices placed in overlapping position, a portion of one of the devices being broken away.

Referring to the drawings: 10, is a base; 11, a standard rising therefrom; 12, a yoke secured to the standard; 13, a reflector pivotally mounted in the upper ends of the yoke 12; 14, the heating unit in the reflector; and 15 is the guard.

The base 10 is preferably triangular in shape so as to permit nesting of a plurality of radiators in a relatively small compass for shipping and storing purposes. By having one point 10^a of the base at the front of the radiator, the radiator is prevented from falling forwardly and setting fire to the surface on which it rests in the event it should be accidentally knocked over.

In the present instance, the reflector 13, having a concave reflecting surface, is formed of sheet metal and adjacent its front edge receives the edge of the guard 15.

In the present disclosure of my invention, I have shown the heating unit 14 as having an insulating support 17 tapering down from a portion near its base towards its tip or outer end and having a spiral groove in which is positioned a resistor 18 comprising a coiled wire. Preferably, the rear end of the support 17 is also tapered down as at 16 and this tapering portion receives one or more convolutions of the resistor 18. The convolution or convolutions of the resistor 18 upon the tapering portion 16 will radiate

light rays onto that portion of the reflecting surface about the base 19 and thus a dark spot which would otherwise be present at the base of the reflecting surface is eliminated. In placing the resistor in the groove 60 of the insulating support 17, the resistor is preferably placed under tension so that the convolutions of the resistor will closely hug the insulating body. With the construction of the heating unit illustrated, a relatively long length of resistor is located within a small compass and the coils of the resistor are securely maintained against movement so that adjacent convolutions cannot come into contact with each other and result 65 in short circuiting. Preferably, the longitudinal center of the resistor 18 is substantially coincident with the axis of the reflecting surface and the diameters of the convolutions of the resistor increase from the forward 70 end of the unit to the portion of greatest diameter adjacent the rear end thereof, so that when the heater is viewed from a position directly in front thereof, substantially 75 the entire length of the resistor which when heated gives out a red glow, may be observed 80 resulting in a pleasing ocular effect. It will be seen from the drawings that the resistor is of greater diameter than the depth of the groove receiving the same so that the convolutions protrude outwardly beyond the 85 surface of the support 17.

The heating unit 14 has a base member 19 provided at its forward end with lugs 22 which fit in notches or recesses in the resistor support 17 to prevent the latter from turning. As most clearly shown in Fig. 3, the base member has a circumferential rib or flange 20 the forward face of which engages 90 about the edge of the opening in the reflector in which the base member is positioned. The base member 19 is held in place by a metal ferrule or shell 21 preferably formed 95 of sheet metal and pressed into shape to provide a socket for receiving the rear end of the base member and a flange curved similarly to the reflector so as to engage thereagainst, the flange being fastened to the reflector by any suitable securing means such as bolts and nuts 23. If desired a spring 100 washer 24 may be interposed between the shell 21 and the base member to prevent rattling of the latter. Carried by the base member are terminal posts 25 which receive the connection plug (not shown) on the end of 105

the cord connected to the circuit wires. These posts have their forward ends threaded so as to be received by internally threaded bushings 26 located in enlarged counterbores of 5 openings 26^a and secured in position therein by bolts 27 passing through the openings 26^a. For the purpose of securing the resistor support 17 to the base 19, there is provided a bolt 28 extending centrally through the insulator and into a centrally disposed opening 28^a in the base, and a nut 29 within a counterbore of this opening 28^a. The rear end of the resistor 18 is connected by a terminal wire 18^a to one of the posts 25 and the 10 forward end of the resistor is connected to the other terminal post by a terminal wire 18^b passing through the support 17.

The guard 15 is convex so as to extend away from the plane of the front face of the 20 reflector and thus prevent wearing apparel or the like from coming into such proximity with the heating unit as to be ignited. Preferably, the guard is removable and its convexity corresponds to the concavity of 25 the reflector so that it may be reversed and in its reversed position nest within the reflector, as most clearly shown in Fig. 7, for shipping and storage purposes.

The guard preferably consists of an outer 30 ring 30 of such size as to fit within the edge of the reflector when it is sprung into position therein; a central ring 31 of such size as to receive the heating unit when the guard is reversed and nested in the reflector, and 35 guard wires 32 between the two rings. The guard wires are preferably formed in pairs, each pair being made by bending a wire back upon itself into "hairpin" shape, the advantage of this construction being that 40 the wires will be securely held in place against twisting movement about the points where they are connected to the rings. The inner ring has a number of spaced fingers 33, alternate fingers being passed through 45 and bent around the closed ends of the hairpin members and intervening fingers being positioned between the guard wires of adjacent hairpin members. The outer ends of 50 the guard wires are passed through openings in the outer ring and then bent over to lie close against the ring, as clearly shown in Fig. 2.

The means for removably securing the 55 guard in place may, of course, be varied, but by preference these means comprise lugs 34 carried by the ring 30 and received by slots 35 in the reflector. Each of the lugs is notched as at 36 so as to receive an edge of a 60 slot 35. Preferably the lugs are disposed at diametrically opposite points on the ring 30 and the notch 36 in one of the lugs is at the lower edge thereof and the notch in the other lug is at its upper edge thereof so that the notches receive the edges of the 65 slots 35 upon a slight rotary movement of

the guard in the direction of the notches. For the purpose of securely holding the guard against accidental displacement upon the reflector, the diametrical distance between the lugs 34 when the guard is not in place upon the reflector is slightly greater, as shown by dotted lines Fig. 1, than the diametrical distance between the slots 35, thus necessitating a slight compression of the guard to permit insertion of the lug 75 into the slots 35 and then when the force of compression is removed, the guard will tend to spring outwardly causing the lugs to frictionally engage against the walls of the slots 35. 80

It will be seen from the drawings and particularly from Figs. 1 and 2, that the centrally disposed opening of the guard, this opening being provided in the present instance by the ring 31, is in axial alinement 85 with the heating unit, and as the surface of the support 17 on which the resistor is mounted tapers downwardly towards its outer or forward end, the entire length of the resistor may be viewed through the 90 opening. Furthermore, the opening in the inner ring 31 is adapted to receive the heating unit to permit nesting of the guard in the reflector.

The manner in which radiators constructed in accordance with the present invention may be overlapped or nested to secure compactness for the purpose of shipment is clearly shown in Fig. 7 wherein the guards 95 15 are nested in the reflectors, and the reflectors are opposed to each with bases 10 in contact.

It is of course obvious that my invention is susceptible of various modifications and changes which are within the spirit of the 105 invention without departing from the scope of the following claims, it being understood that the present disclosure of my invention is by way of illustration only and it is not to be taken as restrictive of my conception. 110

I claim as my invention:—

1. In an electrical heater, a reflector having a concave reflecting surface, a heating unit arranged axially thereof, a convex guard removably secured to the marginal edge of said reflector and having a centrally located opening in alinement with said heating unit, said guard being nestable within said reflector, and a support for said reflector having a triangular base with one of 115 its apices extending forwardly of said reflector.

2. In an electrical heater, a reflector, a resistor support, a resistor on said support, a base member secured to said reflector, interlocking lugs and recesses between said support and base member, and means for securing said support and base member in assembled position. 125

JOSEPH F. LAMB.
